COMBINED COCKING DEVICE AND REAR SIGHT FOR GUNS

Frederick W. Woodhull, Millington, N. J., assignor of three per cent to Frank Hovey Roof Connell, Denning, N. Y., two per cent to Dryden Kuser, as trustee, and one and one-half per cent to Louise M. Kuser, both of Bernardsville, N. J.

Application April 23, 1941, Serial No. 389,841

8 Claims. (Cl. 42—16)

This invention is directed particularly to a combined rear sight and cocking device for a breech block.

An object of the invention resides in the provision of such a device that is so constructed and related to the breech block and stock extension that the breech block may be manually drawn to a cocked position thereby and will automatically return the device to its normal position upon the first movement of the breech block to its breech closing position.

A further object of the invention resides in so correlating the parts that the sight will be unaffected by the subsequent movements of the breech block to either breech closing or breech opening positions.

Another object of the invention resides in so constructing and mounting the device that its accidental movement from normal position will be prevented.

It is also an object of this invention to provide a device of the character referred to that may be incorporated either in new or already constructed guns.

A still further object of the invention is to so construct the device that the opening through the stock extension or receiver through which the connection to the breech block extends will be sealed at all times when the device is in its normal position.

With the above and other objects in view the invention consists of the combination and arrangement of parts set forth in the appended claims, but it is to be understood that certain changes may be made within the scope of the claims without departing from the terms or spirit thereof.

In the drawing:

Figure 1 is an elevation of a gun of the type wherein a reciprocable breech block is forced to its retracted or breech opening position during automatic action by the recoil of the gun, and is forced to its breech closing position by a mechanical means such as a spring;

Figure 2 is a fragmentary plan view of the cocking means;

Figure 3 is a section on line 3—3 of Figure 2, but partly broken away;

Figure 4 is a section on line 4—4 of Figure 3; and

Figure 5 is a section on line 5—5 of Figure 3.

The gun that I have illustrated in the drawing to show the applicability of the invention includes a barrel 1, cooling fins 2, a forward sight 3, a compensator 4, a shoulder or butt stock 5

having a forward extension or receiver 6, a front stock 7 and a pistol grip 8.

In the form of gun that is here illustrated the breech block 9 is slidably mounted in the stock extension 6, which acts as a receiver, and is provided with a forward extension 10 that is slideable within a recess in the front stock 7. A rod 11 is secured in a forward projection of the stock extension 6 or receiver at 12 and projects forwardly where it is provided with a head 13 adapted to abut against a shoulder or a recess in the breech block extension 10. A spring 14 surrounds the rod 11 abutting at its forward end against the shoulder 15 in the extension 10 of the breech block, and at its rearward end against a washer 16 between which and the projection of the breech block a shock absorber 17, preferably of rubber, is interposed.

This arrangement of breech block and its actuating mechanism is similar to that disclosed in my co-pending application 338,890, filed June 5, 1940. The spring 14 operates to move the breech block into its breech closing position after it has been forced into its retracted position by the action of the chamber pressure after firing. The gun may be provided with an action mechanism at 18 of any desired form, and this, too, may be of the form disclosed in said co-pending application.

The combined rear sight and cocking device includes a body portion 19 that is provided with a cylindrical sight opening 20, the forward face 21 of said body portion being curved. An extension 22 projects forwardly from the body portion and an extension 23 rearwardly therefrom.

The body portion 19 and the extensions 22 and 23 are provided with a dovetailed groove 24 in their lower faces which coacts with a track 25 of complementary configuration to permit the body portion and extensions to slide upon the rear stock extension 6 and to keep the sight opening 20 in proper alignment. This track 25 may be secured to the extension 6 on the receiver by any suitable means as, for instance, by such means as screws 27, which are illustrated.

In order that the breech block may be retracted for initial cocking against the action of the spring 14, I have provided the forward end of the extension 22 with a finger 28 which slidably engages in a notch 29 in the forward upper end of the breech block 9, which notch 29 is open at its forward or breech end.

Thus when the curved surface 21 of the body portion 19 is engaged by the finger of the operator, or when the body portion is otherwise engaged

and drawn rearwardly against the action of the spring 14, the combined sight and cocking device will move rearwardly until the finger 22 engages the rear end of the slot 29. Further movement will draw the breech block 9 rearwardly against the action of the spring 14 until the breech block reaches its cocking position and is engaged by the detent mechanism to which I have already referred, the finger 28 sliding in the slot 28' which is formed in the rear stock or shoulder extension 6 or in the receiver.

When the gun is fired by the pulling of the trigger and the breech block 9 moved forwardly under the action of the spring 14 that has been compressed during the rearward movement of the breech block, the breech block will carry the sight and cocking device forwardly because of the engagement of the finger 28 in the slot 29. However, during the subsequent reciprocations of the breech block under the alternate actions of the chamber pressure and the spring 14, the sight and cocking device will remain stationary because of the fact that the slot 29 is open at its forward end and will, therefore, not engage the finger 28 to cause rearward movement of the sight and cocking device.

In order that there may be no accidental displacement of this combined sight and cocking device during the operation of the gun, I have provided a latch 30 which is pivoted at 31 on the body portion 19. This latch carries a pawl 32 that is adapted to engage in a notch 33 in the track 25 and that is normally urged into engaging position by a spring 34 whose tension may be adjusted by a set screw 35.

This latch is also provided at the opposite end with a knurled finger piece 36, pressure on which will oscillate the latch about its pivot 31 and disengage the pawl 32 from the notch 33 against the tension of the spring 34.

This disengaging movement of the pawl is limited by the engagement of a projection 37 on the latch, which projection is adapted to engage the upper face of the track 25, as indicated in Figure 5 of the drawing.

It will be noted that the combined rear sight and cocking device is adapted for application to new or already constructed guns, for the breech block, the receiver or the rear or shoulder stock extension may be recessed to receive the finger 28 and the track 25 may be secured to the rear stock extension or receiver without material alteration of the latter.

Moreover it is to be noted that the device will be held securely in position during the automatic reciprocation of the breech block, so that there will be no disturbance of the alignment of the rear sight with the forward sight.

It is also to be noted that the slot 28', through which the finger 28 extends, will be closed during the normal operation of the gun by the extension 22.

What I claim is:

1. In a gun, a receiver having a slot extending longitudinally thereof in its upper wall; a reciprocable breech block mounted in said receiver and having a notch in its forward end located in registry with the slot in the receiver; a combined rear sight and cocking device mounted on the upper face of the receiver and including an upwardly extending body portion having a sight opening therein, a finger projecting through the slot in the receiver into the path of travel of the breech block and adapted to engage the breech block to move it into cocked position and to lie

in the notch in the breech block when the latter is in its breech closing position; and means for securing the rear sight and cocking device to the outer face of the receiver to permit it to slide longitudinally thereof.

2. In a gun, a receiver having a slot extending longitudinally thereof in its upper wall; a reciprocable breech block in said receiver having a notch in its forward end located in registry with the slot in the receiver; a combined rear sight and cocking device mounted on the upper face of the receiver and including an upwardly extending body portion having a sight opening therein, a finger projecting through the slot in the receiver into the path of travel of the breech block, said finger being adapted to engage the breech block to move it into cocked position and to lie in the notch when the breech block is in its breech closing position; means for securing the rear sight and cocking device to the outer face of the receiver to permit it to slide longitudinally thereof; and means for locking the rear sight and cocking device with the finger thereof at the forward end of the travel of the breech block.

3. In a gun, a receiver having a slot extending longitudinally thereof in its upper wall; a reciprocable breech block in said receiver having a notch in its forward end located in registry with the slot in the receiver; a combined rear sight and cocking device mounted on the upper face of the receiver and including an upwardly extending body portion having a sight opening therein, a finger projecting through the slot in the receiver into the path of travel of the breech block, said finger being adapted to engage the breech block to move it into a cocked position and to lie in the notch when the breech block is in its breech closing position, an extension covering the slot in the receiver except during the cocking operation; and means for securing the rear sight and cocking device to the outer face of the receiver to permit it to slide longitudinally thereof.

4. In a gun, a receiver having a slot extending longitudinally thereof in its upper wall; a reciprocable breech block in said receiver having a notch in its forward end located in registry with the slot in the receiver; a combined rear sight and cocking device mounted on the upper face of the receiver and including an upwardly extending body portion having a sight opening therein, a finger projecting through the slot in the receiver into the path of travel of the breech block, said finger being adapted to engage the breech block to move it into a cocked position and to lie in the notch when the block is in its breech closing position, an extension covering the slot in the receiver except during the cocking operation; means for securing the rear sight and cocking device to the outer face of the receiver to permit it to slide longitudinally thereof; and means for locking the rear sight and cocking device with the finger thereon at the forward end of the travel of the breech block.

5. In a gun, a receiver having a slot extending longitudinally thereof in its upper wall; a reciprocable breech block in said receiver having a shoulder thereon; a combined rear sight and cocking device mounted on the upper face of the receiver and including an upwardly extending body portion having a sight opening therein, a finger projecting through the slot in the receiver into the path of travel of the breech block and adapted to engage the shoulder on the

breech block to move the latter into a cocked position and to be free of the breech block when the latter is in its breech closing position; and means for securing the rear sight and cocking device to the outer face of the receiver to permit it to slide longitudinally thereof.

6. In a gun, a receiver having a slot extending longitudinally thereof in its upper wall; a breech block in said receiver; a plate mounted on the outer upper face of said receiver; and a combined rear sight and cocking device mounted on the upper face of the receiver and including an upwardly extending body portion having a sight opening therein and having a dovetailed and sliding connection with said plate and a finger extending through the slot in the receiver and in separable engagement with the breech block.

7. In a gun, a receiver having a slot extending longitudinally thereof in its upper wall; a reciprocable breech block in said receiver; a plate mounted on the outer upper face of said receiver; and a combined rear sight and cocking device

mounted on the outer upper face of said receiver and including an upwardly extending body portion having a sight opening therein and having dovetailed and sliding connection with said plate,

5 a finger extending through the slot in said receiver and having separable engagement with the breech block and an extension adapted to cover the slot in the receiver except during the cocking operation.

10 8. In a gun, a receiver; a reciprocable breech block mounted in said receiver; and a combined rear sight and cocking device mounted on the upper face of said receiver for sliding movement longitudinally thereof and having an upwardly extending body portion with a sight opening therein, and a separable connection with the breech block whereby the breech block may be moved rearwardly to a cocked position and disengaged from said combined rear sight and

15 cocking device when the latter is moved to its forward position.
